UNITED STATES PATENT OFFICE.

THOMAS H. FURMAN, OF SEWARD, DISTRICT OF ALASKA.

STAMP AND ENVELOP MOISTENER.

No. 863,599.

Specification of Letters Patent.

Patented Aug. 20, 1907.

Application filed October 26, 1906. Serial No. 340,760.

To all whom it may concern:

Be it known that I, THOMAS H. FURMAN, a citizen of the United States, residing at Seward, in the Territory of Alaska, have invented new and useful Improvements in Stamp and Envelop Moisteners, of which the following is a specification.

This invention relates to a device for applying postage stamps to mail matter and is also applicable for use in moistening envelop flaps or for any other purpose 10 where it is desired to apply moisture.

The primary object of the invention is to provide a device of the class set forth having a simple and effective construction and capable of ready operation.

The improved device includes essentially a body 15 having a blotting paper support or holder and a tube with a valve in one end normally held closed by a spring and provided with an exteriorly-projecting stem carrying a sponge or other absorbent material.

The invention also consists in the details of construction and arrangement of the several parts which will be 20 more fully hereinafter set forth.

In the drawing—Figure 1 is a top or plan view of a device embodying the features of the invention. Fig. 2 is a longitudinal vertical section of the same.

25 Similar characters of reference are employed to indicate corresponding parts in the views.

The numeral 1 designates a body of suitable material having a reduced or flanged base 2 provided with seats or recesses 3 in the upper surface at the center near opposite ends to receive the terminals 4 of a bowed spring plate 5 to which a strip 6 of blotting paper is applied and secured by doubling the same over the ends 4 and forcing the latter ends with the blotting paper thereon into the recesses or seats 3. The body strip 5 is constructed of suitable spring metal and may be readily applied to or removed from the flanged base 2.

On the top of the body 1 a tube 7 is secured and held in place by embracing bands 8, the tube 7 having at one end a removable cap 9 and its opposite end 10 reduced by tapering or giving it a semi-conical contour.

In the reduced or tapered end 10 of the tube a conical rubber valve member 11 is movably disposed and has an inwardly-projecting shank 12, over which is fitted one end of an elongated coiled spring 13, the opposite 45 end of said spring bearing against a washer or disk 14, held by the cap 9 against the adjacent end of the tube 7. The valve 11 also has an outwardly projecting stem 15 of such diameter that it will readily move through the front reduced extremity of the end 10, and 50 on the stem 15 is secured a sponge 16 or other suitable absorbent material. The stem 15 is of the same material as the valve 11, all the parts of the valve including the shank 12 and the stem as well as the intermediate body or valve proper are constructed of rubber.

55 The use of a rubber valve is particularly advantageous in that a snug closure or sealing of the end of

the tube 7 will result when the spring 13 is free to force the valve forward to its seat in the reduced end or extremity of the said tube.

Furthermore in the use of the improved device or 60 moistener the stem 15 yields slightly when the sponge is drawn over the envelop or other material to apply a stamp or brought into contact with the gummed side of a stamp, or when used for sealing envelop flaps.

In preparing the device for use the tube 7 is supplied 65 with a quantity of water which is introduced therein by removing the cap 9 and the washer or disk 14, the latter acting as a water-tight joint forming means when the cap is applied. After water has been disposed in the tube 7 the improved device may be turned up and 70 conveniently held to bring the sponge 16 in contact with the surface of an envelop or other matter, an envelop flap or the gummed side of a stamp and moisture applied to the point desired.

In some operations a strip of stamps may be held in 75 one hand and the improved device or moistener in the other hand and a rapid application of the stamps may thus be pursued. By pressing against the sponge 16 the valve 11 is forced upwardly into the tube and a portion of the liquid is permitted to escape and drop on the 80 sponge. After the sponge is relieved of pressure the valve 11 immediately assumes a normal position and closes the end of the tube so that leakage of the contents of the tube is obstructed. In the event that too much moisture may be applied to a letter or paper or an 85 envelop flap the excess moisture may be removed by pressing the blotting paper 6 held by the metal strip 5 against the moistened surface.

The improved device will be found exceptionally 90 convenient and it is proposed to use materials in the manufacture of the same best adapted for the purpose. The tube 7 may be formed either of metal or glass, glass being shown as used in the present instance. It is also proposed to vary the proportions, dimensions 95 and details without departing from the spirit of the invention.

What I claim is—

A body having a terminally flanged base provided with seats or recesses, a spring metal strip having its ends formed for engagement with said seats, a blotter applied to 100 the strip and attached thereby to the base, a tube mounted on the upper side of the body and having at one end a removable closure cap and at its other end a reduced discharge opening, a valve fitted in and for normally closing said opening, said valve having a projecting stem carrying 105 an absorbent material, and a normally expanded spring arranged in the body and bearing on the valve for holding the latter yieldably closed.

In testimony whereof, I affix my signature in presence of two witnesses.

THOMAS H. FURMAN.
